CLAIM

The ornamental design for a fluid mixer, as shown and described.

DESCRIPTION

FIG. 1 is a top perspective view of the fluid mixer showing our new design; the rod being shown in dotted lines for illustrative purposes only and forming no part of the claimed design;

FIG. 2 is a bottom perspective view thereof; the rod being shown in dotted lines for illustrative purposes only and forming no part of the claimed design;

FIG. 3 is a front elevation view thereof; the rear elevation view being a identical image thereof;

FIG. 4 is a top plan view thereof;

FIG. 5 is a bottom plan view thereof;

FIG. 6 is a bottom perspective view of a second embodiment of our new design; the rod shown in dotted lines for illustrative purposes only and forming no part of the claimed design;

FIG. 7 is a top perspective view thereof; the rod being shown in dotted lines for illustrative purposes only and forming no part of the claimed design;

FIG. 8 is a front elevation view thereof; the rear elevation view being a identical image thereof;

FIG. 9 is a top plan view thereof; and,

FIG. 10 is a bottom plan view thereof.
